UNITED STATES PATENT OFFICE

152,501

DESIGN FOR PANTIES

Anna Mae Sebastian, Cairo, Ill.

Application February 27, 1948, Serial No. 144,779

Term of patent 14 years

(Cl. D3—17)

To all whom it may concern:

Be it known that I, Anna Mae Sebastian, a citizen of the United States, residing in Cairo, Illinois, have invented a new, original, and ornamental Design for Panties, of which the following is a specification, reference being had therein to the accompanying drawing, forming a part thereof.

Fig. 1 is a front view of a pair of panties, embodying my design.

Fig. 2 is a rear view of the panties appearing in Fig. 1.

I claim:

The ornamental design for panties, as shown.
ANNA MAE SEBASTIAN.
